JOSEPH H. MADISON, OF WHITMANS, WEST VIRGINIA

RAIL TRACK

Application filed April 12, 1929. Serial No. 354,569.

My present invention has reference to a track construction for mines, and my primary object is the construction and arrangement of parts whereby the rails in a mine 5 may be extended by the employment of supplemental rails without interfering with the permanent rails of the track.

A further object is the provision in a construction of this type, of means for effectively and securely clamping the main rails on the ties, and such means being also utilized for supporting extension rails which are rotated to a right angle with respect to the main rails so that the wheels of the mine 15 cars can travel off of the main rails and onto the webs of the extension rails when the track is to be temporarily extended, regardless of the different lengths of projections of the ends of the main rails.

20 To the attainment of the foregoing and other objects which will present themselves as the nature of the invention is better understood, the improvement also resides in certain other novel features of construction, combination and operative association of parts, a satisfactory embodiment of which is disclosed by the accompanying drawings.

In the drawings:

Figure 1 is a plan view of the improvement. 30 Figure 2 is an enlarged detail plan view to better illustrate the manner in which the extension rail is secured on the tie and associated with the main rail.

Figure 3 is a sectional view approximately on the line 3—3 of Figure 1.

Figure 4 is a sectional view substantially similar to Figure 3 but illustrating the arrangement of parts when the extension rail is projected beyond the main rail.

40 Figure 5 is a view substantially similar to Figures 2, 3 and 4, but showing the arrangement of parts when only the main rail is clamped to the tie.

45 Figure 6 is a perspective view of the filler block member employed.

Figure 7 is a fragmentary side elevation of one of the clamps, with the tie in section, to illustrate the clamp being integrally formed 50 with a seat to be received in a depression in

the tie and holding the clamp in either of its two positions.

Figure 8 is a sectional view approximately on the line 8—8 of Figure 7.

As the description progresses it will be noted that either the main rails or the extension rails may be easily, quickly and securely clamped to the ties.

The ties are of the usual channeled metal members and are indicated by the numeral 1. On each of the ties, adjacent to the ends thereof there are fixed transversely arranged blocks 2. For the sake of convenience I will refer to these blocks as filler blocks. The blocks have their inner faces straight and are 60 notched in a line with the lower edges, as indicated by the numeral 3. The upper walls provided by these notches are inclined, and the notches are designed to normally receive therein one edge of the base flange 4 of what 70 I will term the main or permanent rails 5 of the track. The second edge of the base flange 4 of the rails 5 is adapted to be engaged by the notched ends 6 of plates 7 which 75 I will refer to as clips. As stated, the blocks 2 are firmly riveted to the ties but the plates 7 are pivotally secured to the said ties, as indicated by the numerals 8. Suitable means, such as either fixed or removable pivots 9, hold the clips longitudinally on the ties and 80 the lips 6 thereof in firm engagement with the inner base flanges of the rails 5.

Except for the inner straight face, the spacer blocks 2 (which are of a length corresponding approximately with that of the 85 width of the tie) have their upper and outer faces shaped to correspond with the shape of the fishing space of a rail, and when the track is to be extended, such rails indicated by the numeral 10 and arranged rightangularly with 90 respect to the rails 5, and having their heads received in the outer fishing spaces of the said rails 5, rest upon the blocks 2 and have one of the edges of their base flanges resting on the tie. In this instance the pivot pins 9 for the 95 clips are removed and the clips are swung to a position reverse to that previously described. By reference to the drawings it will be seen that the pivot 8 is disposed close to the rail engaging lip 6 of the clip 7, and by reference 100

especially to Figure 4 of the drawings it will be seen that when the clip is reversed the second and non-notched end of the clip will be in a position to provide a rest for the under side of the head 11 of the rail 10. In this instance, the pivot pin 9 is passed through the same opening through the clip but through a second opening in the tie.

Pivoted secured, as at 12, on the top of the tie 1, adjacent to each of the outer ends thereof there is the base flange 13 of an angle clamp. The upper or vertical arm 14 of this clamp merges into an offset lip 15 designed, when the clamp is swung to the position illustrated in Figures 1, 2, 3 and 4 of the drawings, to be brought over the upper edge of the base flange of the extension rail 10. The pivot 8 and the pivot 12 are each preferably in the nature of double headed rivets and the base 13 of the swingable base flange engaging clamp for the rail 10 is held in such engagement by a removable pin 16.

Obviously in lieu of the locking pins 9 and 16, of the blocks or clips 7 and the base flanges of the angle clamps may be in the nature of lugs or stubs movable into depressions in the upper face of the tie, and when the swingable clamp 14 is not employed and the same is arranged transversely of the tie, as disclosed by Figure 5 of the drawings, either the pin 16 or the lugs are again brought into engagement with the tie to hold the said clamps in such position.

By reference to Figure 1 of the drawings it will be seen that the extension rails may be connected to the permanent rails regardless of the difference between the projecting ends of the said main rails. The construction is extremely simple and may be easily operated to firmly secure both the main and the extension rails on the ties and will permit of the easy and quick removal of such rails from the ties.

While I have herein set forth a satisfactory embodiment of my improved device, my features of invention are capable of extended application and, therefore, I do not wish to be restricted to the precise details herein set forth and, therefore, hold myself entitled to make such changes therefrom as fairly fall within the scope of what I claim.

While I have referred to the holding means for the clamps and clips as being in the nature of removable pins, it will be apparent and as disclosed by Figures 7 and 8 of the drawings that the base of either the clamp or clip may be formed with a depending teat 17 and the top of the tie is formed with depressions or sockets 18 to receive the teats therein.

With this arrangement it will be necessary that an impact of force, such as a blow from a hammer, be directed against one side of the clamp or clip for moving the same to either of its operative positions or for holding the same out of operative position.

Having described the invention, I claim:

1. In a mine track, metal ties upon which fixed rails rest, notched blocks fixed on the ties for receiving the inner base flanges of the rails in the notches thereof and the webs of the rails being disposed away from the notched edges of the blocks, plates comprising rail engaging clips having one of their edges notched to receive the outer base flanges of the rails therein and being pivoted to the ties in close proximity to said notches, the blocks designed to provide rests for the webs of extension rails, when the latter are turned to a right angle and arranged thereover, the heads of the extension rails, when so positioned being received in the fishing spaces of the fixed rails, clamps on the ties for engaging with the base flanges of the extension rails for holding the same on the blocks, and said clips when turned on their pivots end for end designed to provide rests for the heads of the extension rails at the portions thereof received on the ties beyond the ends of the fixed rails.

2. In a mine track, metal ties upon which fixed rails rest, notched blocks fixed on the ties for receiving the inner base flanges of rails in the notches thereof and having their inner edges spaced away from the webs of the rails, plates comprising rail engaging clips having one of their edges notched to receive the outer base flanges of the rails therein and being pivoted to the ties in close proximity to said notches, the blocks designed to provide rests for the webs of extension rails, when the latter are turned to a right angle and arranged thereover, the heads of the extension rails, when so positioned being received in the fishing spaces of the fixed rails, clamps on the ties for engaging with the base flanges of the extension rails for holding the same on the blocks, and said plates when turned on their pivots end for end designed to provide rests for the heads of the extension rails at the portions thereof received on the ties beyond the ends of the fixed rails and locking means for the plates and clamps.

In testimony whereof I affix my signature.
JOSEPH H. MADISON.
